UNITED STATES PATENT OFFICE

168,294

DISPLAY CONTAINER

Benjamin B. Fort, Greensboro, N. C., assignor to
Vick Chemical Company, New York, N. Y., a
corporation of Delaware

Application February 26, 1952, Serial No. 18,673

Term of patent 14 years

(Cl. D80—5)

To all whom it may concern:

Be it known that I, Benjamin B. Fort, a citizen of the United States, residing at R. F. D. 8, Box 262, Greensboro, North Carolina, have invented a new, original, and ornamental Design for a Display Container, of which the following is a specification, reference being had to the accompanying drawing, forming a part hereof.

Fig. 1 is a front perspective view of a display container showing my new design;

Fig. 2 is a front elevational view; and

Fig. 3 is a side elevational view thereof.

I claim:

The ornamental design for a display container, as shown.

BENJAMIN B. FORT.
